(Cl. D2—320)

FIG. 1 is a bottom plan view of a sole for a ski boot embodying my design,

FIG. 2 is a side elevational view of the sole for a ski boot shown in FIG. 1, and

FIG. 3 is a cross-sectional view taken along the line 3—3 of FIG. 1.

The distinctive feature of the design is that the inner edge of the tread surface of the sole of the ski boot is defined by a straight line extending from the toe to the heel of the sole with the outer edge being defined by two straight lines of different lengths extending from the toe to the heel and converging adjacent the ball portion of the foot.

I claim:

The ornamental design for a sole for a ski boot, as shown and described.
